UNITED STATES PATENT OFFICE.

JOHN A. SPENCER, OF LONG BEACH, CALIFORNIA.

LEAD-JOINT RUNNER.

1,420,586.

Specification of Letters Patent. Patented June 20, 1922.

Application filed March 24, 1921. Serial No. 455,119.

To all whom it may concern:

Be it known that I, JOHN A. SPENCER, a citizen of the United States, residing at Long Beach, in the county of Los Angeles and State of California, have invented new and useful Improvements in Lead-Joint Runners, of which the following is a specification.

It is the object of this invention to provide a lead joint runner which includes a recessed annulus received upon the inner one of overlapping pipe sections, so that packing may be received within said recess and against the end of the overlying pipe section in order to provide a space adapted to receive the lead.

It is a further object of the invention to provide extremely simple but efficient means for retaining the recessed annulus in position and to generally improve and simplify the construction of the lead joint runner so as to form an inexpensive and practical device.

The invention will be readily understood from the following description of the accompanying drawings, in which—

Figure 1 is a longitudinal section through overlapping pipe sections showing the lead joint runner in operative position.

Fig. 2 is a longitudinal section on the line 2—2 of Fig. 1.

Fig. 3 is a transverse section on the line 3—3 of Fig. 2.

Fig. 4 is a detail section on the line 4—4 of Fig. 3.

Fig. 5 is a detail transverse section through a portion of the recessed annulus forming a part of the lead joint runner and showing the means of retaining the packing within the recess.

Fig. 6 is a similar view showing the overlapping ends of the packing within its recess.

The lead joint runner is illustrated as employed in connection with pipe sections 1 and 2 having a usual overlapping end joint which includes an enlarged end flange 3 upon one of the pipe sections, shown as the section 2, and received over the end of the other pipe section 1.

The lead joint runner includes an annulus 4 which is formed in two sections hinged together as shown at 5 and adapted to be received around pipe 1 just beyond flange 3. This annulus includes a base portion and a peripheral flange 6 so that an annulus is

provided which is recessed at its side turned toward flange 3.

A second annulus 7 is mounted upon the flange 3 and includes sections hinged together as shown at 8. This annulus fits snugly upon flange 3 so as to impinge against enlarged collar 9 formed at the end of said flange.

The two annuli are fixed in position upon pipe section 1 and upon flange 3 respectively by providing the swinging meeting ends of the hinged sections of the respective annuli with radially projecting lugs 10. A loop 11 is received over the lugs 10 of each of the two annuli forming the lead joint runner, and these loops are fixed to one of each of the respective pairs of lugs as by reversely bending said lugs as shown at 10^a in order to form bearings for the meeting ends of the members forming the loops. Clamping bolts 12 are threaded through the swinging ends of the loops, received over the other lug of each of the pairs of lugs 10, so as to impinge against said lugs of each pair, and thereby connect the respective swinging ends of the hinged sections forming annuli 4 and 7. In order to provide a space for the pouring of the lead, an opening 13 is provided in flange 6 at the ends of the hinged sections forming the annulus 4.

The annuli 4 and 7 are clamped to one another by providing radial ears 15 upon annulus 7 and receiving bolts 16 through said ears with nuts 17 upon the ends of said bolts for securing the same in position. The opposite ends of the bolts extend over annulus 4 with their end portions inwardly bent at such an angle that the extreme ends 18 of the bolts will impinge against the base of annulus 4 adjacent pipe section 1. It will thus be seen that by tightening nuts 17, the two annuli forming the lead joint runner may be drawn toward one another with the pressure of said clamping means received against the base of annulus 4 at the pipe section 1 and thereby in alignment with the lead joint.

In using the improved lead joint runner, the space within recessed annulus 4 between the base of the same and the end of the overlying flange of pipe section 2, is filled with a suitable packing in order to form a closed space between pipe section 1 and flange 3 for receiving the lead forming the joint. This packing may be in the form of rope shown at 21 and extends around annulus 4

with the ends of the packing overlapping, as clearly shown in Fig. 6, in order to provide a tight joint while permitting of some circumferential adjustment of the packing. 5 This packing may be held in position by means of cotter pins 22 received through the packing and through suitable openings provided in the peripheral flange of annulus 4 and provided with flattened heads 25 engaging the packing.

It will be understood that the lead joint runner may be made in various suitable sizes in order to adapt the same for various sizes of pipe joints.

15 In practice the packing for the lead joint runner is preferably made in two semi-circular sections in order that it may be more readily placed in position within the runner.

Various changes may be made without departing from the spirit of the invention as 20 claimed.

What is claimed is:

1. A lead joint runner for overlapping pipe sections comprising a recessed annulus 25 upon the inner pipe section and having its periphery overlying the outer pipe section, packing within the recess of said annulus abutting against the end of the outer pipe section, and means for securing said annulus 30 in position.

2. A lead joint runner for overlapping pipe sections comprising a recessed annulus upon the inner pipe section and having its periphery overlying the outer pipe section,

packing within the recess of said annulus 35 abutting against the end of the outer pipe section, means for attaching said packing to said annulus, and means for securing said annulus in position.

3. A lead joint runner for overlapping 40 pipe sections comprising a recessed annulus upon the inner pipe section, an annulus upon the outer pipe section, and bolts connected to said second annulus with their ends angularly disposed and impinging 45 against the back of the first annulus.

4. A lead joint runner for overlapping pipe sections comprising a recessed annulus upon the inner pipe section, an annulus upon the outer pipe section, and bolts connected 50 to said second annulus and impinging against the back of the recessed annulus at the extreme ends of said bolts which are adjacent the inner pipe section.

5. A lead joint runner for overlapping 55 pipe sections comprising a recessed annulus upon the inner pipe section, an annulus upon the outer pipe section, said annuli comprising hinged sections, means for connecting the swinging ends of the hinged sections of 60 the respective annuli, and clamping means for connecting said annuli.

6. A lead joint runner including a recessed annulus adapted to receive a packing annulus having overlapping ends. 65

In testimony whereof I have signed my name to this specification.

JOHN A. SPENCER.
